UNITED STATES PATENT OFFICE.

VAN AMBURGH LECHNER, OF COLUMBUS, OHIO, ASSIGNOR TO HIMSELF AND
FRANCIS M. LECHNER.

MINING-MACHINE.

SPECIFICATION forming part of Letters Patent No. 295,183, dated March 18, 1884.

Application filed March 31, 1883. (No model.)

To all whom it may concern:

Be it known that I, VAN AMBURGH LECHNER, of Columbus, in the county of Franklin and State of Ohio, have invented a new and useful Improvement in Mining-Machines; and I do hereby declare the following to be a full, clear, and exact description of the invention, reference being had to the accompanying drawings, forming a part of this specification, in which—

Figure 1 is a plan view of my improved mining-machine. Fig. 2 is a vertical longitudinal section on the line *a a* of Fig. 1. Fig. 3 is a vertical longitudinal section on the line *b b* of Fig. 1. Fig. 4 is a side view of the outer bearings of the screw and driving-shaft. Fig. 5 is a cross-section on the line *c c* of Fig. 1. Figs. 6 and 7 are views of the chain and cutters. Fig. 8 is a perspective view of the traveling carriage. Fig. 9 is an end view of one of the sliding chain-carriers, partly in section. Fig. 10 is a central cross-section of Fig. 9.

Like letters of reference indicate like parts in each.

The characteristic features of my invention consist of endless chains carrying cutters, such chains operating in pairs and working the cutters from a central point or point of impact outward, so that the pressure of the opposite cutters which are operating in the rock shall be against each other, and thereby relieve the machine of the pressure and permit it to retain its position, and also so that the cuttings shall be thrown outward and clear of the machine. The chains are mounted on suitable moving frames, whereby they are advanced as the cutters penetrate the coal or other material, and they are driven by suitable wheels from the same shaft by which the feeding mechanism is driven.

To enable others skilled in the art to make and use my invention, I will now describe it by reference to the accompanying drawings.

The machine has a stationary frame or bed-plate, 1, upon the sides of which are two standards or brackets, 2, one on each side, for supporting the steam or air cylinders 3 and 4, by which the machine is driven.

Bolted to the bed-plate 1, near one end, is a vertical frame or casting, 5, in which bear-

ings 6, for the driving-shaft and screw, are formed. At the other end is a frame or casting, 7, also bolted to the bed-plate, in which are formed the outer bearings of the shaft and screw.

Mounted in bearings 8, at one end of the machine, is a power-shaft, 9, which is driven by the steam or air cylinders 3 and 4, by cranks 10 at the opposite ends, two engines quartering with each other being used, for the reason that a fly-wheel to carry a single engine over the dead-point cannot be used, because the cutters are liable to strike an obstacle or piece of hard rock and stop, and cause the machine to be broken by the force or momentum of the wheel. The power-shaft is provided with a beveled pinion, 11, which gears into a beveled wheel, 64, mounted on the end of a shaft, 12, extending lengthwise of the machine, said shaft being journaled in the vertical castings or frames 5 7 in bearing 6. The shaft 12 is driven by the power-shaft 9, and in turn drives the chains and the feeding devices. It is key-seated throughout the greater part of its length, and is provided with a beveled pinion, 15, for purposes to be explained. Placed alongside of the shaft 12 in bearings 6 in the same frames 5 and 7, but in a lower horizontal plane, is a screw-shaft, 17, mounted loosely on the end of which, directly under the worm 13 on the power-shaft 9, is a worm-wheel, 18. On the same shaft, 80 inside of the worm-wheel, is a sliding clutch, 19, which is connected to the shaft by a feather-key, and inside of the clutch is a gear-wheel, 20, which is mounted loosely on the shaft, but is in gear with a gear-wheel, 21, mounted on the shaft 12. The sides of the worm-wheel 18 and gear-wheel 20, adjacent to the clutch 19, are provided with engaging-teeth, so that the clutch can be thrown into gear either with the gear-wheel or with the worm-wheel. When it 90 engages the worm-wheel, the shaft 17 is driven from the shaft 9, by means of the worm 13, mounted thereon and of the worm-wheel 18, and this causes it to turn in the proper direction to feed the cutters forward; and when the clutch 19 engages the gear-wheel the shaft 17 is driven from the shaft 12, by means of gear-wheels 21 and 20, in the reverse direction, which reverse movement effects the withdrawal of the cutters. The shaft 17 is placed at a lower level 100

than the shaft 12, to permit of the worm-wheel 18 being placed under the worm 13 on the shaft 9, which is not necessary with the shaft 12, as it is driven by the bevel-pinion 11, and consequently can be on the same level.

It is now in order to describe the cutters and the mechanism for operating them.

The stationary frame 1 has two guide plates or ways, 23, extending longitudinally along its inner edges. Resting on these ways are two flat sliding bars or carrying-arms, 24, which at their inner ends are bolted to a sliding frame, 25. The base-plate 26 of the sliding frame 25 is provided with flanges 27, which have the double function of affording means for the attachment of the carrying-arms 24 and of extending under the ways 23 to hold the sliding frame down. Stepped in the bed-plate 26 are two vertical shafts 28 and 29, the upper ends of which are journaled in the top plate, 30, of the sliding frame. On each shaft 28 and 29 are sprocket-wheels 31 and gear-wheels 32, the latter meshing into each other. On the upper end of the shaft 28 is a beveled-gear wheel, 33, which meshes with the beveled pinion 15, mounted on the shaft 12.

Extending between the standards 34 on the frame 35 is a trough, 35, semicircular in cross-section. This trough stands between the vertical shafts 28 and 29, being on a lower level than the beveled-gear wheel 33, and on a higher level than the gear-wheel 32 on the shorter shaft 29. The standards 34 of the frame 25 are bored at the ends of the trough for the passage of the screw-shaft 17, which extends also through the trough.

On the inner faces of the standards 34, above the trough 35, are guides 22, and placed in these guides is a semicircular nut, 36, which fits down on the screw-shaft 17, being held in place by a lever, 37, which is pivoted to a bar, 16, extending between the standards 34. The nut has a pin, 38, which projects into a slot 39, in the lever. When the lever is depressed the nut is thrown into gear with the screw, and when the lever is raised the nut is raised off the screw.

On the outer end of each of the sliding bars or carrying-arms 24 are two sprocket-wheels, which are mounted in the following manner: A cross-bar or plate, 40, is secured to the under side of each sliding arm. On top of the sliding arm a block, 41, is placed, and on top of the block 41 is a second plate, 42, similar to the plate 40. The plates 40 and 42 and block 41 are all firmly secured to the carrying-arm 24 by riveting, or in any desirable way, so as to make a compact and strong structure. Between the outer ends of the plates 40 and 42 are shafts or journals 43, upon which the sprocket-wheels 44 and 45 are loosely mounted. The inner edge of the sprocket-wheels 44 are nearly in line with the inner edge of the sprocket-wheels 31.

On the outer edges of the carrying-arms 24, near to the wheels 31, are sprocket-wheels 46, the purpose of which is to support and pre-

vent the sagging of the chains as they pass over the edges of the frame. The outer sprocket-wheels 45 stand beyond the outer edges of 70 the frame 1.

The chains 47 are of peculiar construction. They are composed of links 48, pivoted together by rivets 49. Each link is provided with a cutter, 50, which is keyed in, as at 51, 75 or secured in any other suitable manner. When made up into a chain, 47, the ends of the adjacent links overlap each other, so that the rivets 49 pass through the adjacent ends, which are placed side by side. This construction leaves an open space, 52, between the ends of alternate links. Outside of this open space and overlapping the adjacent ends of the alternate links is a steel plate, 53, which is secured in place by the same rivet, 49, that 85 passes through the ends of adjacent links, so that when the complete chain is made, each rivet passes first through a plate, 53, which extends in one direction, a link 48 extending in the opposite direction, a second link 48 extending in the direction of the first plate, and a second plate 53 extending in the direction of the first link 48. In such a chain the cutters 50 are arranged zigzag. The same is also true of the spaces 52, so that there is a cutter 95 and a space opposite to each other in every compound link or section shown. The sprocket-wheels are constructed with reference to this peculiarity of the chain, being provided with spurs or teeth 54, arranged in a zigzag 100 manner upon its periphery. These teeth take into the open spaces 52 and draw the chain around. The direction of the movement of the chains is indicated by the arrows. They pass from the sprocket-wheels 31 down the middle 105 of the machine in lines parallel with the ways 23, around the wheels 44, thence at right angles around the wheels 45, and thence by the wheels 46 to the sprocket-wheels 31 again. The points of the cutters 50 extend forward, and 110 when the machine is placed to cut against a breast of coal or other material, they strike the coal by a direct blow or impact, and then pass outward from the point of impact in opposite directions, so that the pressure of the 115 cutters on one chain is against that of the cutters on the other chain, and all danger of the displacement of the machine is entirely obviated. The effect of this motion is also to cause the cuttings to be carried outward and discharged outside of the machine, so that the machine is constantly clearing itself, and is not liable to become clogged or impeded in any way by the cuttings.

The peripheries of the sprocket-wheels 44 125 and 45 project slightly in advance of the outer face of the block 41 and the outer edges of the plates 40 and 42. To prevent the chain while passing between the wheels 44 and 45 from pressing back into the recess or space thus left 130 between the two wheels and shrinking from its work, I bolt or otherwise fasten to the outer face of the block 41 a plate, 55, which is of sufficient thickness to stand flush with the pe-

ripheries of the wheels 44 and 45. This plate will keep the cutters up to their work by holding the chain in a straight line, and thereby preventing its yielding to the pressure.

5 In order to keep the chains at a proper tension, I have provided the following tension device: At the inner ends of the sliding bars 24 I make a perforated lug, 56, and on the base-plate 26 of the sliding frame 25 I make 10 similar lugs, 57, which extend out into line with the lugs 56, and are tapped and threaded. In the lugs 56 I place screws 58, the threaded portions of which extend forward through the lugs 57, and engage the threads therein. In 15 the sliding bars 24 I make slots 59, two or more, as may be necessary, of a length slightly in excess of the length of one of the links of the chain. Extending up from the base-plate 26 of the sliding frame 25 are threaded bolts 20 60, provided with nuts 61. The operation of this device is as follows: If any slack should occur in the chains it can be taken up by loosening the nuts 61 and then turning the screws 58, so as to project the sliding bars 24 25 farther outward. When the movement has been sufficient to take up the slack and tighten the chains, the nuts 61 are screwed down, so as to fasten securely the sliding frame 25 and the bars 24 together.

30 I will now describe a particular construction I have adopted for journaling the sprocket-wheels at the outer ends of the sliding bars 24. This construction is shown in Figs. 9 and 10. Placed loosely inside of the sprocket-wheels 35 is a thimble, 62, which is internally threaded. This thimble being placed inside of the sprocket-wheel, the latter is slipped sidewise into place between the plates 40 and 42, and then two screws, 43, are inserted through the plates 40 from opposite sides, one of the screws being put through the plate 40 and the other through the plate 42. These screws are screwed tightly into the thimble 62, and fasten it rigidly in place between the two plates. The sprocket-wheel being loose on the thimble turns freely 45 on it, while the thimble serves to support the outer ends of the plates and keep them from binding upon the edges of the wheels. The advantages of this construction are that I 50 secure the easy removal and replacement of the sprocket-wheels, which, being subject to great strain, are more or less liable to wear and injury. Moreover, the spindles of the wheels being removable without the necessity of disturbing the attachment of the plates 40 and 42 to the sliding bar 24, I am enabled to rivet 55 them permanently to the bar, and thus make a much stronger and more desirable construction. The outer heads of the screws 43, coming flush with the face of the plates 40 and 42, give a smooth surface, and thus enable the 60 sliding bars to move in and out of the cut without impediment, and cause it to work with great nicety. The chains are of the same width as that of the sprocket-wheels 44 and 65 45, with their plates 40 and 42.

The operation of the machine is as follows:

The clutch 19 is thrown in gear with the worm-wheel 18. The worm-wheel 18 and the shaft 12 are driven by the shaft 9. The power to 70 operate the wheels which turn the chains is taken from the shaft 12 by means of the beveled pinion 15. At the rear side of the pinion 15 is one of the standards 63 of the sliding frame 25. As before stated, the pinion 15 is 75 keyed to the shaft 12 and turns with it. It meshes into the beveled gear-wheel 33 on the upper end of the shaft 28, and causes the shaft 28 to turn, and thereby operates the vertical shaft 29 by means of the gear-wheels 32. The 80 sprocket-wheels 31, being mounted on the two vertical shafts 28 and 29, are turned thereby and move the chains in the direction of the arrows. It is necessary to advance the sliding frame with its bars 24 toward the breast 85 of coal or other material being cut as the cutting progresses. The rate of this advance depends upon the nature of the material upon which the machine is being used. With hard material it is necessarily slow, while with 90 softer material it may be increased correspondingly. This advance is made by means of the screw 17 and nut 36, the construction of which has been described. The screw 17 is operated by means of a worm, 13, mounted 95 on the shaft 9, meshing into a worm-wheel, 18, mounted loosely on the outer end of the screw 17. The clutch 19, being thrown into gear with the worm-wheel 18, causes the screw 17 to be turned, and the thread of the screw 17, acting 100 upon the thread of the nut 36, moves the sliding frame 25, with its bars 24, outward. When the sliding frame has traveled the desired distance outward, and it is necessary to cause it to be retracted, the clutch 19 is thrown out of 105 connection with the worm-wheel 18 and into connection with the gear-wheel 20. This causes the motion of the screw-shaft 17 to be reversed, and its thread acting in the opposite direction upon the nut 36, causes the sliding frame 25 to be moved inward and to retract the cutters from contact with the rock. When the sliding frame has been drawn entirely back, the entire machine is moved side- 110 wise and caused to operate in the same manner against another portion of the surface of the rock or coal. 115

The outer portion of the cutting-edge of cutter 50 projects beyond the side of the chain, so that the cut in the rock shall be wider than 120 the chain, in order to give clearance to the latter, because there is always a tendency in coal and similar formations of the sides to close inward and reduce the width of the cut. Especially is this the case if the vein of coal rests 125 upon a bed of fire-clay, because the latter will swell as soon as the cut relieves it of a portion of the superincumbent weight, and partially close the cut. My construction of the cutters makes the cut sufficiently wide to allow for 130 this closing, and so prevents danger of the chains becoming jammed or caught therein.

The frame 25 and bars 24 constitute a sliding carriage which sustains and carries the

chains and their actuating mechanism. The cutters in one chain are always made to come opposite to those on the other chain, as illustrated in Fig. 1. In case the work is very severe and the great strain on the cutters causes the ends of the bars 24 to give inward, I can make them support each other against this strain by providing every two or more links, as may be necessary, with projecting blocks on their outer faces, such links having no cutters. Then as the chains move these blocks come together and fill the space between the chains, and prevent the bars from being forced any nearer together or from springing inward.

The purpose of the trough 35 is to give an under bearing to the screw-shaft 17, so as to enable me to use a semicircular or removable nut, 36. It sometimes happens that it is desirable to remove the nut out of gear with the screws to enable the traveling-carriage to be moved backward without operating the machine. The most frequent cause of this is that the rock sometimes falls on the machine in such quantity that it is dangerous to operate the machine until the rock is taken off. In such case the nut 36 may be raised by the lever 37, and the traveling carriage pried back by a crow-bar or other means until it is clear of the débris. When the nut 36 is raised off the screw, the trough 35 supports and sustains the screw while its smooth inner surface presents no obstacle to the backward motion of the carriage over the screw. When the nut is in working position the trough supplies the requisite under-bearing for the screw.

In constructing the machine its various parts should be made powerful enough to enable it to stall the engines, so that, in case the cutters meet an obstacle they cannot overcome, the engines will not be powerful enough to break the machine.

A great advantage of my improvement consists in the fact that the cutters are working successively on the same line of cut, and this enables me to operate the machine with much less power and much more rapidly than in that class of machines having a rotary cutter biting against the rock where the entire length of the cutter is operating at once. Another advantage is that a clean cut is made thereby, and no further work on the breast is necessary at that point. The cutters of the two chains strike the breast side by side at a common point or center, and then turning cut outward in opposite directions a certain determined distance. No core in the middle nor uncut portion at any point in the range of the cutters is left to be subsequently broken down, as is the case when drilling and similar machines are used.

The construction described makes a compact, portable, efficient machine. I obtain the advantage of two cuts by using the two chains; and, as before stated, the making of these cuts in opposite directions from a cen-

tral point takes the strain of the cutters off the machine.

In practice the cutters 50 will not be mounted on every link. In some cases there will be one on every fourth link, and in others a less number.

I am aware that two rotary cutters revolving in opposite directions have heretofore been combined with a carriage provided with mechanism to cause the carriage to advance against the breast of coal, and do not herein claim such devices.

What I claim as my invention, and desire to secure by Letters Patent, is—

1. In a machine for mining coal and like purposes, the combination of two chains provided with cutters and arranged to move in opposite directions in a plane or planes at right angles to the line of advance of the machine, substantially as and for the purposes specified.

2. The combination, in a machine for mining coal and similar substances, of two revolving chains provided with cutters mounted on suitable wheels to communicate motion to them, and moving side by side to the point of cut and then outward in opposite directions, substantially as and for the purposes described.

3. In a machine for mining coal and similar substances, two chains provided with cutters and mounted on suitable wheels for driving them side by side to the point of cut and then outward in opposite directions, in combination with a sliding carriage carrying said chains, and the mechanism for actuating the same, substantially as and for the purposes described.

4. In a machine for mining coal and similar substances, two revolving chains provided with cutters, and mechanism for moving the chains in opposite directions and at right angles to the line of advance of the machine, in combination with a sliding carriage for sustaining the chains and operating mechanism, a nut mounted on said frame, and a screw-shaft coaxing with said nut to move said frame, substantially as and for the purposes described.

5. In a machine for mining coal or similar substances, two revolving chains provided with cutters, and mechanism for causing the chains to travel in reverse directions, in straight lines, and in planes at right angles to the line of advance of the machine, in combination with a stationary power-shaft, and a feather-keyed sliding pinion on said shaft, connected with and actuating the mechanism which operates the chains, substantially as and for the purposes described.

6. In a machine for mining coal and like purposes, the combination of two cutters, and mechanism, substantially as specified, for causing the cutters to move in right lines in opposite directions at right angles to the path of the machine while cutting, substantially as and for the purposes set forth.

7. The combination, in a machine for mining coal and similar substances, of a traveling

carriage carrying two cutter-chains, and mechanism for causing said chains to move in a right line in opposite directions while cutting, a stationary shaft having a sliding key-seated pinion for actuating the chain-revolving mechanism, a nut on said carriage, a screw-shaft co-acting with said nut to move the carriage, in order to feed the cutters to their work, and a power-shaft connected with and driving the other two shafts, substantially as and for the purposes described.

8. The two sliding bars, each provided with two loose sprocket-wheels or chain-sheaves secured at their outer ends in a cross-frame, and arranged parallel with each other, in combination with the two cutter-chains and mechanism to move the latter in opposite directions after reaching the end of the bars, substantially as and for the purposes described.

20 9. The cutter-chain for mining-machines, composed of a series of cutter-links arranged with the lapping ends, and support-plates arranged on the sides of the chain parallel with and opposite to each cutter-link, whereby the

cutters are placed zigzag in the chain, and the 25 sprocket-holes are in line with the cutters, substantially as and for the purposes set forth.

10. The combination, in a machine for mining coal and similar substances, of a pair of cutter-chains moving side by side to the point 30 of impact against the rock, having projecting cutters arranged opposite to each other or at corresponding points on the two chains, substantially as and for the purposes described.

11. The combination, in a machine for mining coal and similar substances, of a pair of cutter-chains moving side by side to the point of impact, and then passing outward in opposite directions, having supporting-blocks placed on the adjacent sides of opposite links, 40 substantially as and for the purposes described.

In testimony whereof I have hereunto set my hand this 23d day of March, A. D. 1883.

VAN AMBURGH LECHNER.
